SUPPRESSING WAX IN OILS

Charles Edwin Francis and Bernard Sutro Greensfelder, Martinez, Calif., assignors to Shell Development Company, San Francisco, Calif., a corporation of Delaware

No Drawing. Application October 22, 1934,
Serial No. 749,499

2 Claims. (Cl. 87—9)

This invention relates to a process for suppressing or inhibiting the formation of solid wax in hydrocarbon oils.

Hydrocarbon oils which contain waxy constituents often lose their lippidity because of the separation of particles of solid wax. This separated wax appears either in the form of a cloud within the oil or as a more or less crystalline precipitate which may remain dispersed throughout the oil. Frequently, the separated wax will be found collecting on the walls of an oil container, especially at the surface of the oil, or rising to the oil surface. Such separation of wax may occur at temperatures which are substantially above the pour point or congealing temperature of the oil, with the result that small constrictions in a lubricating system may become obstructed. The lack of clarity is also undesirable, because of the unattractive appearance of the oil. This is manifested both in the formation of clouds or dispersed more or less crystalline precipitates or in the formation of surface wax.

It is one object of our invention to reduce, delay, or prevent the separation of such particles of wax by the addition of certain innocuous substances to the oil, which are hereinafter referred to as "wax suppressors". Other objects of our invention will be apparent from a reading of this specification.

We have found that the addition of very small quantities of esters of saccharoses with aliphatic acids effects the desired suppression of wax. As used in the present specification and claims, we use the term "saccharose" as a generic term to include both mono- and poly-saccharoses. Examples: Arabinose, lyxose, glucose, fructose, sucrose, avocado sugar and cabbage sugar. The acyl radical should preferably contain between ten and thirty-two carbon atoms and may comprise either a straight or a branched chain, and be either saturated or not. Examples: Palmitic acid, stearic acid, oleic acid, hypogaeic acid, linoleic acid, and other aliphatic and particularly fatty acids. The saccharose should, preferably, contain between four and ten hydroxy radicals, either all or a part of which are then esterified. We have found that best results are achieved when more than three and not more than ten hydroxy groups are esterified.

Examples of saccharose esters are: tetra- or pentastearyl dextrose (glucose d), tetra- or pentastearyl laevulose (fructose d), pentacapryl saccharose, octabehenyl maltose, etc.

We have found tetra- and pentastearyl glucose and octastearyl saccharose (disaccharose) to be

especially effective as wax suppressors, and it is to be understood that a preferred embodiment of our invention comprises the use of these substances.

The effective quantity of wax suppressor required for inhibiting wax formation in different hydrocarbon oils varies with different suppressors and also depends upon the quantity and the nature of the wax in the oil. We have found that usually the effective amounts vary between 0.05% and 1.5% of the oil.

Such quantities of wax suppressors, as are used according to this invention, have no significant effect upon the pour point of the oil, but have a marked effect in preventing or retarding the separation of wax. When used in excessive concentrations, the wax suppressors may or may not exhibit pour point reducing properties. In general, we found that the property of inhibiting the formation of wax is not necessarily accompanied by the property of reducing pour points of wax-containing oils. Thus, a number of known pour point reducers were tried on several oils, but failed to suppress the separation of wax at temperatures above pour points of the oils.

The wax suppressors may be added to the oil either at ordinary or at elevated temperatures. If the oil being treated contains particles of separated solid wax, it is generally desirable to warm the oil to dissolve the wax prior to its treatment.

A particular advantage of the use of the esters of our invention is that they do not appreciably darken the color of the oil. Since most of them are of a light color, and are effective although used in quantities of the order of 1.5% or less, they usually cause no color change when used to suppress the formation of wax.

To illustrate the use and effect of our wax suppressors, the following examples are presented:

Example I

An Edeleanu raffinate from Coalinga distillate, having a viscosity of 500 sec. S. U. at 100° F., when stored at 40° F., clouded overnight, but samples to which 0.1% of pentastearyl glucose had been added remained clear for over two weeks. Adding larger amounts up to 1% was likewise found to be effective to suppress wax.

Example II

A similar raffinate, when kept at temperatures of about 40° F. became obscured because of the formation of a dull waxy surface. When 0.25% of octastearyl saccharose was added to the oil this formation was prevented, and the addition of

smaller amounts delayed the formation of this dull surface, although it did not entirely prevent it. The addition of 1% of "Paraflo" (a condensation product of a waxy hydrocarbon material with an aromatic hydrocarbon), a known pour point reducer, had no retarding effect on this precipitation of wax.

Example III

10 The addition of 0.5% of octastearyl saccharose prevented the formation of suspended wax crystals in Coalinga Edeleanu raffinate at a temperature of about 50° F. for one month, although the original oil became obscured in two days. The addition of 1% of "Paraflo" had no effect.

15 *Example IV*

A Coalinga Edeleanu raffinate showed turbidity and cloudiness after two days storage at 70° F. The addition of 0.1% of pentastearyl glucose to 20 samples of the same raffinate caused them to remain clear for over 100 days at 70° F.

25 *Example V*

25 A Coalinga Edeleanu raffinate showed turbidity and cloudiness after two days storage at 70° F. The addition of 0.1% of octastearyl saccharose to samples of the same raffinate caused them to remain clear for over 130 days.

30 While these particular examples demonstrate the effectiveness of stearic acid-glucose and of stearic acid-sucrose condensation products, our invention is not limited thereto, as other saturated

and unsaturated monobasic aliphatic acids, having from ten to thirty-two carbon atoms, may be used.

Instead of the particular aldo-hexose and the dihexose, other keto or aldo monosaccharoses or polysaccharoses may be used.

As used in the present specification and claims, the expression "suppression of wax" means the prevention, reduction or retardation of the formation of solid wax in a body of oil.

Although we have heretofore disclosed that esters of mono- and poly-saccharoses are suitable for suppressing wax, we have found that the ester of mono- and of di-saccharose is especially useful for this purpose.

10 15 We claim as our invention:

1. A limpid oil composition comprising a mineral oil containing wax in amount and composition normally to cause visible wax to separate from the oil in a solid state at temperatures above 20 the pour point of the wax-containing oil, and a small quantity of pentastearyl glucose to suppress the said separation of visible wax.

2. A limpid oil composition comprising a mineral oil containing wax in amount and composition normally to cause visible wax to separate from the oil in a solid state at temperatures above the pour point of the wax-containing oil, and between 0.05% and 1.5% pentastearyl glucose to suppress the said separation of visible wax.

25 30 CHARLES EDWIN FRANCIS.
BERNARD SUTRO GREENSFELDER.
